CLAIM

The ornamental design for a mobile terminal, as shown and described.

DESCRIPTION

FIG.1 is a front perspective view of a mobile terminal of the present invention;

FIG. 2 is a top perspective view thereof;

FIG. 3 is a rear perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is an enlarged view of portion of FIG. 1 thereof.

The broken lines shown represent unclaimed subject matter and form no part of the claimed design. Additionally, the unevenly broken lines in the drawings define the limits of the claimed design.
